ROTATABLE STORAGE CABINET

Vernoy A. Reihmer, 9502 Dodson Way,
Villa Park, Calif. 92667

Filed Mar. 8, 1966, Ser. No. 1,346

Term of patent 14 years

(Cl. D33—19)

FIG.1

FIG.2

FIG.3

FIG.4

FIGURE 1 is a perspective view of a rotatable storage cabinet according to the present invention;

FIGURE 2 is a front elevational view of such cabinet showing one side of the rotatable storage means thereof;

FIGURE 3 is another front elevational view showing the rotatable storage means rotated 180 degrees from its position in FIGURE 2; and

FIGURE 4 is a side elevational view of said cabinet as shown in FIGURE 3 of the drawings.

I claim:

The ornamental design for rotatable storage cabinet, substantially as shown.
